UNITED STATES PATENT OFFICE.

PHILIP GERMAIN, JR., OF NEW YORK, N. Y.

DISPLAY STAND.

Application filed June 3, 1926. Serial No. 113,364.

This invention relates to an improved pedestal or support adapted for use in advertising, and is herein disclosed as a display stand for an elastic vehicle tire.

5 It is an object of the invention to provide a pedestal of the above-described character, which may be made of relatively light and inexpensive material in a form adapted to be folded into minimum space for shipping, but so constructed as to support a relatively heavy tire without undue distortion.

Another object of the invention is to provide a support or pedestal of the character described, having four well-defined reinforced points of support so disposed as to maintain other parts of the stand free from the surface on which it rests.

A still further object of the invention is to provide a display stand comprising pivoted elements so formed as to serve as jaws or grippers adapted to be operated by the weight of the article to be supported and to be closed into a grasping relation therewith, the pivoted portions of said elements being so disposed as to maintain a vertical position best adapted to transmit the weight of the supported article to the underlying points of support, and being reinforced to strengthen the pivotal connections and prevent distortion of the parts of the structure upon which the displayed article is intended to rest.

The sides and ends of the pedestal afford appropriate space for advertising matter relative to the article supported thereby.

In the drawings illustrating the preferred form of the invention,—

Figure 1 is a perspective view of a pedestal embodying the invention, a fragmentary portion of a vehicle tire supported thereby being indicated in broken lines.

Fig. 2 is a cross-sectional view of the pedestal, the section being taken along the plane represented by the line 2—2 of Fig. 3.

45 Fig. 3 is a longitudinal sectional view of the pedestal along the plane represented by the line 3—3 of Fig. 2.

Fig. 4 is an enlarged sectional view of one of a pair of pivotal connections uniting the parts of the pedestal, the section being taken along the plane indicated by the line 3—3 of Fig. 2.

Figs. 5 and 6 are sectional views on an enlarged scale, taken along the planes indicated respectively by the lines 5—5 and 6—6, Fig. 2.

Fig. 7 is a side view of the pedestal with the parts indicated as being folded to a closed position.

Fig. 8 is a top view of the folded pedestal indicated in Fig. 7.

As indicated by the above-described figures of the drawing, the pedestal in its preferred form comprises two elements 20, each of which may be cut from a single blank of material such as fibre-board, press-board, papier-mâché, or other material having equivalent properties of toughness, rigidity and flexibility. Each of the elements 20 may comprise a pair of end portions 21 and an intermediate portion 22 connected along lines of the material which may be weakened, as at 23, by indentation, scoring or the like, so as to form hinge-like joints between the end portions and the intermediate portions. Preferably the elements 20 will be of such form that, when opened out into a single plane, no part of the end portions will extend beyond a pair of parallel lines separated by a distance equal to the width of the intermediate portions, and the lines of weakness which form the hinge-like joints will be disposed at right angles to said parallel lines.

In the form of the invention herein disclosed, the end portions 21 of the pedestal elements are reinforced by having additional layers of material 24 secured thereto by appropriate fastening devices 25, 26, 27, and the free ends of the portions 21 and their reinforcing layers are overlapped and interleaved in alternation and united by the connecting elements 27 to pivotally connect the pedestal elements as at 28, as most clearly indicated in Fig. 8. These pivotal connections may be further reinforced by the use of washers 29 of relatively large diameter, which may be placed against the surfaces of the reinforcing elements and against which the ends of the fastening devices 27 may be clinched.

As clearly indicated in Figs. 1, 2 and 7, the end portions 21 may be cut to appropriate form to serve as a pair of jaws or grippers 30 adapted to receive the tire or other article to be displayed, and the lower margins of the end portions may be cut to such form that all parts thereof, except rounded portions 31 adjacent their hinge connections to the intermediate portions of the pedestal elements, will be maintained free from contact with the surface on which the pedestal

is supported. These rounded portions 31 serve as downwardly-directed legs or points of support so disposed as to maintain all other parts of the pedestal free from the supporting surface and cause it to rest upon four widely spaced points of support.

If desired, the legs or supporting surfaces 31 may have metal reinforcements 32 extended from the fastening elements 26 into close proximity with their effective bearing surfaces. Such reinforcements are herein disclosed in the form of washers which may surround the fastening elements 26 and may be interposed between the end portions of the pedestal elements and their adjacent layers of reinforcing material.

With the parts of the pedestal constructed as herein described, it may be opened from the form indicated in Figs. 7 and 8 to the form indicated in Figs. 1, 2, and 3 adapted to support a tire 33, represented fragmentarily in broken lines in Figs. 1 and 3. The parallel relation which exists between the lines of weakness forming the hinge-like joints between the end portions of the pedestal elements and their intermediate portions causes the end portions, when turned and united in overlapped relation, to be maintained in a vertical plane, as clearly indicated in Figs. 1 and 3. This vertical position of the end portions is the one best adapted to transmit the load of the article to be supported to the legs or supports 31 with the least tendency to distort the material, and, by reinforcing these load-supporting end portions, especially the parts thereof which are connected to provide the pivotal connections between the pedestal elements, the remaining portion of the pedestal may be made of relatively light material.

The relation between the grippers 30, the pivotal connections at 28, and the points of support 31 is such that the weight of the tire when placed upon the pedestal will tend to depress the pivotally-connected ends of the pedestal elements and cause the grippers 30 to be closed into a grasping relationship with the adjacent surfaces of the tire, whereby the same will be firmly held in an upright position.

By so forming the lower margins of the end portions of the pedestal elements as to provide well-defined points of contact adjacent the hinge connections between the ends and intermediate portions of the pedestal elements, tires of widely varying sizes may be supported in the pedestal, which, under all circumstances, will be supported at four well-defined widely-spaced points of contact.

The above-described pedestal may readily be folded to a form convenient for storage and packing. This is effected by first rotating the pedestal elements about their pivotal connections 28 until the intermediate por-

tions of the pedestal elements 22 lie in parallel planes, after which the elements may be flattened down about two of the oppositely-disposed hinge joints 23, the other two being opened up until the parts of the pedestal assume the position indicated in Figs. 7 and 8, in which all parts thereof lie within the width of the intermediate portions of the pedestal elements.

The invention is not limited to the preferred form of the invention herein disclosed for purposes of illustration, but is intended to include modifications and variations within the scope of the appended claims.

What is claimed is:

1. A foldable display pedestal comprising a pair of elements made of material having substantially the rigidity, toughness and flexibility of fibre-board, said elements having end portions and intermediate portions connected along lines of the material weakened, as by scoring, to form hinge-like joints, said end portions being bent at said lines of weakness into planes substantially perpendicular to the planes of the intermediate portions, the bent end portions being reinforced by having additional layers of material secured thereto and having their free ends overlapped and pivotally connected so as to form two oppositely-disposed sides of the pedestal having parts relatively movable about aligned axes, each of the pivotally-connected end portions being so formed as to provide a pair of upwardly-extending grippers and a pair of downwardly-directed widely separated supports, whereby the weight of an article supported in said grippers will tend to depress the unsupported pivoted portions of the pedestal elements and thereby cause the grippers to close and firmly grip the supported article.

2. A foldable display pedestal, as defined by claim 1, comprising elements of each of which the intermediate portion and its end portions, if restored to their original flat relationship, would lie within a pair of parallel lines coincident with the edges of the intermediate portion, the lines of weakness forming the hinge-like joints between the end and intermediate portions of said elements being perpendicular to said parallel lines, whereby the elements of said pedestal may be moved about their two pivotal connections to the positions such as to bring their intermediate portions into parallel planes and then folded into a flat relationship with the inner surfaces of pairs of adjacent sides in contact and all parts of the pedestal confined within the width of the intermediate portion of one of its elements.

3. A foldable display pedestal, as defined by claim 1, of which the end portions of the elements, and their reinforcing layers, have their free ends interleaved in alternation and

secured by the fastening elements forming the pivotal connections between the pedestal elements.

4. A foldable display stand, as defined by
5 claim 1, of which the end portions of the
elements, and their reinforcing layers, have
metal fastening elements to secure them to-
gether, one of said fastening elements being
located near each of the parts of the pedestal
10 elements forming the downwardly-directed
supports, and having a metal reinforcement
extending therefrom into close proximity
with the supporting surfaces.

15 5. A foldable display stand, as defined by
claim 1, of which the end portions of the
elements, and their reinforcing layers, have
metal fastening elements to secure them to-
gether, one of said fastening elements being
located near each of the parts of the pedestal
20 elements forming the downwardly-directed
supports, and having a metal reinforcement
extending therefrom into close proximity
with the supporting surfaces, said metal re-
inforcement comprising a washer, surround-
25 ing the fastening element and interposed be-
tween the end portion of the pedestal ele-
ment and its adjacent layer of reinforcing
material.

30 6. A foldable display pedestal comprising a pair of elements made of material having substantially the rigidity, toughness and flexibility of fibre board, said elements having end portions and intermediate portions connected along lines of the material weakened, as by scoring, to form hinge-like joints, said end portions being bent at said lines of weakness to an angular relationship with respect to the intermediate portions, the bent end portions being reinforced by having additional layers of material secured thereto and having their free ends, and the free ends of their reinforcing layers, overlapped and interleaved in alternation and pivotally connected so as to form two oppositely-disposed sides of the pedestal, each of the pivotally-
35
40
45

connected end portions being so formed as to provide a pair of upwardly-extending grippers and a pair of downwardly-directed widely-separated supports, whereby the weight of an article supported in said grippers will tend to depress the unsupported pivoted portions of the pedestal elements and thereby cause the grippers to close and firmly grip the supported article.

7. A foldable display pedestal comprising a pair of elements made of material having substantially the rigidity, toughness and flexibility of fibre board, said elements having end portions and intermediate portions connected along lines of the material weakened, as by scoring, to form hinge-like joints, said end portions being bent at said lines of weakness to an angular relationship with respect to the intermediate portions, the bent end portions being reinforced by having additional layers of material secured thereto by metal fastening elements, and having their free ends overlapped and pivotally connected so as to form two oppositely-disposed sides of the pedestal, each of the pivotally-connected end portions being so formed as to provide a pair of upwardly-extending grippers and a pair of downwardly-directed, widely-separated supports, one of the fastening elements being located near each of said supports, and having a relatively rigid reinforcement extending therefrom into close proximity with the supporting surfaces.

8. A foldable display stand, as defined by claim 7, of which the relatively rigid reinforcements in the parts forming the downwardly-directed supports comprise washers surrounding the fastening elements and interposed between the end portions of the pedestal elements and their layers of reinforcing material. 80 85

In witness whereof, I have hereunto signed my name.
